UNITED STATES PATENT OFFICE.

UBALD HEBERT, OF MANCHESTER, NEW HAMPSHIRE.

TRANSFERRING MECHANISM FOR AUTOMATIC FILLING-REPLENISHING LOOMS.

No. 896,014.

Specification of Letters Patent.

Patented Aug. 11, 1903.

Application filed October 25, 1907. Serial No. 399,128.

To all whom it may concern:

Be it known that I, UBALD HEBERT, a citizen of the United States, residing in Manchester, in the county of Hillsboro and State of New Hampshire, have invented new and useful Improvements in Transferring Mechanism for Automatic Filling-Replenishing Looms, of which the following is a specification.

10 This invention relates to transferring mechanism for the purpose mentioned in which the mechanism transfers automatically a fresh filling-carrier from the hopper or the filling-feeder to the shuttle at the proper time, the transfeerer comprising a rocking-arm or lever which is adapted by means of intermediate mechanism to engage the filling-carrier by its head and tip and transfer it from the hopper or filling-feeder to the shuttle; and the present invention has for its object to provide mechanism which is simplified in construction, efficient and certain in operation, and not liable to get out of repair.

15 The nature of the invention is fully described in detail below, and illustrated in the accompanying drawings, in which:—

20 Figure 1 is a cross-sectional view looking toward the right of a portion of a loom provided with automatic filling-supplying mechanism, the section being taken between the end-plates of the hopper or filler, and the transferring mechanism being shown in normal open position—the whole embodying my invention. Fig. 2 is a side elevation in detail showing the jaws of the transfeerer locked on the bobbin or filling-carrier. Fig. 3 is a detail view in side elevation showing the filling-carrier inserted in the shuttle with the tip-grasping mechanism in releasing position and the transfeerer ready to return to its normal position. Fig. 4 is a view of the bobbin or filling-carrier to be transferred, looking toward the left, and with the tip-grasping mechanism in the position indicated in Fig. 2.

25 Similar numerals of reference indicate corresponding parts.

Reference numeral 10 represents a portion of the frame of the loom, 11 is a portion of the lay, 12 is one of the shuttle-boxes slotted at the bottom for the passage of the ejected filling-carrier, 13 is the self-threading shuttle and 14 is the hopper or filling-feeder of which a portion only of the inner disk 15 is illustrated.

30 16 represents the filling-carriers held in the

hopper by their ends, the heads 17 being in one plate and the tips 18 in the other. Rigid on a stand 19 is a stud 20 on which is pivotally mounted the transfeerer consisting of 35 the two arms 21 and 22, the lower depending arm 22 carrying a notched dog 23 to be engaged by a bunter 24 on the lay when a change of filling is to be effected.

All the designated parts, and their operation, are known in the art, and they are not claimed as new in this invention.

Rigidly secured to the arm 21 of the transfeerer is one end (the right hand end) of a horizontal rod or shaft 25, and rigid on the 40 opposite end of this shaft is a downwardly extending plate 26 whose lower end is hollowed up or concaved at 27, thereby producing two downward extensions 28 and 29. The downward extension 29 is tooth-shaped and hook-shaped, and constitutes a stationary jaw, and the other extension 28 has pivoted to it at 30 a cam 31, from which cam extends downward the curved movable jaw 32, and integral with said cam is an arm 33 and a tooth or dog 34. Pivoted at 35 to the plate 26 above the cam 31 is an arm consisting of the two parts 36 and 37 substantially at right angles with each other, the part 36 being provided on its lower edge with 45 a notch 38 and the tooth 39. This arm is held normally down by a spring 40 extending therefrom to the shaft 25, such normal position being illustrated in Fig. 1 in which the inner edge of the portion 37 of the arm bears 50 against the outer edge of the movable jaw 32, and the under edge of the tooth 39 bears against the upper edge of the tooth 34, preventing the tooth 34 from slipping into the notch 38.

55 In Fig. 1 the tip-grasping mechanism is in its normal position, that is to say, the position in which it remains until the filling is exhausted or nearly so and the filling-carrier is ready to receive a fresh supply. While the shuttle is moving toward the right, provided its filling is nearly or quite exhausted, the automatic filling mechanism raises the dog 23 in the manner well known in the art from its normal position in Fig. 1, and the bunter 60 24 as the lay beats up reaches and touches the dog, and begins to move it until the arm 21 of the transfeerer swings downward causing the stationary jaw 29 and the movable jaw 32 to drop on opposite sides of the tip 18 65 of the filling-carrier or bobbin until the arm 33 which is rigid with the movable jaw

strikes the tip 18 and is forced up into the position indicated in Fig. 2, the tooth 34 slipping under and by the tooth 39 until it catches in the notch 38, thus locking the jaws 5 on opposite sides of the tip and enabling them to grasp it—the parts being then in the position indicated in Fig. 2. As the bunter continues to move, the dog 23 is swung into the position indicated in Fig. 3, and the arm 10 21 is swung down as shown in said figure, the downward swinging of said arm causing the lower end of the portion 37 of the bent arm 36 to come into contact with the shuttle-box 12 and to yield and be forced up against the power of the spring 40 into the position indicated in said Fig. 3, releasing the cam 31 by lifting the tooth 39 out of engagement with the tooth 34, and thus freeing the bobbin or filling-carrier from the tip-grasping 15 20 jaws 32 and 29. The automatic-mechanism is timed so that when the parts are in the position indicated in Fig. 1 the lay is back to its farthest point, as is also the crank, and as the parts leave the position shown in Fig. 1 the 25 shuttle starts from its box at the left toward the right end of the loom; when the parts are in the position indicated in Fig. 2 the lay is a little more than one-half the distance of its throw forward and the crank is down; 30 when the parts have reached the position indicated in Fig. 3 the lay is forward and the crank is half way up; when the crank is swinging up on the third quarter of its turn the lay is swinging back and arrives one-half 35 the way back when the crank has reached its highest point; and when the crank is moving rearward on the last quarter of its turn the replenished shuttle is returning to its box at the left end of the loom—all of which movements are produced by mechanism well known in the art and substantially described in United States Letters Patent numbered 724,121 and 647,918.

When the jaws are in the act of disengaging the tip, the raising of the arm 36, 37 in disengaging the tooth 34 from the tooth 39 causes the lower end of the movable jaw 32 to rise a little, raising the tip, and facilitating the engagement of the rings on the head of 56 the bobbin with the bobbin-holder.

Having thus fully described my invention, what I claim, and desire to secure by Letters Patent, is:—

1. In a transferring mechanism for automatic filling-replenishing looms, a rocking-arm, a downwardly extending bar rigid on the rocking-arm and terminating in a stationary jaw adapted to extend into the shuttle, an arm pivoted to said bar and adapted 55 to extend over the shuttle-box, a movable jaw pivoted to the said bar on the same plane 60 as the arm, and means for holding the arm

against the outer edge of the movable jaw until said arm is relatively raised by contact with the shuttle-box as the two jaws descend 65 into the shuttle.

2. In a transferring mechanism for automatic filling-replenishing looms, a rocking-arm, a downwardly extending bar rigid on the rocking-arm and terminating in a stationary jaw adapted to extend into the shuttle, an arm pivoted to said bar and adapted to extend over the shuttle-box, a movable jaw pivoted to the said bar on the same plane as the arm, means for holding the arm against 70 the outer edge of the movable jaw when the arm is above the shuttle, means for locking the two jaws as they descend on opposite sides of the filling-carrier tip and holding the same in locked position until said arm is relatively raised by contact with the shuttle-box 75 as the two jaws descend into the shuttle.

3. In a transferring mechanism for automatic filling-replenishing looms, a rocking-arm, a downwardly extending bar rigid on the rocking-arm and terminating in a stationary jaw adapted to extend into the shuttle, an arm pivoted to said bar and located over the shuttle-box, a cam pivoted to the said bar and provided with a downwardly 80 extending jaw which is movable with relation to the stationary jaw and further provided with an extension which is normally over the filling-carrier tip, and oppositely projecting teeth formed on the adjacent edges of said 85 cam and arm, whereby the said parts provided with the teeth are locked together when the jaws are grasping the tip but are separated when the jaws descend into the shuttle by the relative raising of said arm. 90

4. In a transferring mechanism for automatic filling-replenishing looms, a rocking-arm, a downwardly extending bar rigid on the rocking-arm and formed with a downwardly extending and inwardly curved stationary jaw, a cam pivoted to the said bar and comprising an upwardly extending tooth, a downwardly extending inwardly curved movable jaw and a substantially horizontal extension over the filling-carrier tip, an arm 105 pivoted to the bar above the cam and provided with a downwardly extending tooth and formed downward toward and above one side of the shuttle-box, and a spring holding said arm normally down against the cam, 110 for the purpose set forth.

In testimony whereof I have signed my name to this specification in the presence of two subscribing witnesses.

UBALD HEBERT.
